CLAIM

We claim the ornamental design for a bicycle transit strap, as shown and described.

DESCRIPTION

FIG. 1 is a perspective view of a bicycle transit strap in a buckled position;

FIG. 2 is a front view of the bicycle transit strap in a buckled position;

FIG. 3 is a right side view of the bicycle transit strap in a buckled position;

FIG. 4 is a left side view of the bicycle transit strap in a buckled position;

FIG. 5 is a back view of the bicycle transit strap in a buckled position;

FIG. 6 is a perspective view of the bicycle transit strap in an unbuckled position;

FIG. 7 is a front view of the bicycle transit strap in an unbuckled position;

FIG. 8 is a right side view of the bicycle transit strap in an unbuckled position;

FIG. 9 is a left side view of the bicycle transit strap in an unbuckled position; and,

FIG. 10 is a back view of the bicycle transit strap in an unbuckled position.

The broken lines shown in the figures are for the purpose of illustrating environmental structure and form no part of the claimed design.
